UNITED STATES PATENT OFFICE.

SIEGFRIED DEUTSCH, OF VIENNA, AUSTRIA.

DEVICE FOR REGULATING THE AIR SUPPLY TO FURNACES OF STEAM BOILERS.

Application filed June 23, 1920. Serial No. 391,249.

To all whom it may concern:

Be it known that I, SIEGFRIED DEUTSCH, mech. engineer, citizen of the Republic of Austria, residing at Vienna, Lower Austria, 5 Austria, have invented certain new and useful Improvements in Devices for Regulating the Air Supply to Furnaces of Steam Boilers, of which the following is a specification.

This invention relates to devices for regulating the air supply to furnaces of steam boilers the object being to provide an improved device for maintaining a predetermined steam pressure in the boiler.

In the known regulating devices of this kind, a member is provided which is moved to different positions by and in conformity with the variations of the pressure of the steam in the boiler and varying thereby the cross-section of the air passage leading to the furnace of the steam boiler; these devices have the drawback that the raise and fall of the steam pressure in the boiler are proportionally transmitted to the regulating member, that is to say, a gradually increasing of the boiler pressure causes a gradual movement of the regulating member for closing the air passage and vice versa. Therefore a slow or lingering opening and closing of the air supply passage is produced, which 25 is practically not very suitable for maintaining a fixed, predetermined pressure in the boiler.

By means of the present invention the following results are obtained: 1/ the air supply passage to the furnace remains totally open until the desired steam pressure in the boiler is attained, 2/ that the air supply is rapidly stopped, when the steam pressure in the boiler rises above the desired pressure, 40 and 3/ that the air supply passage is rapidly reopened when the pressure falls below the desired value, so that the steam pressure may be maintained substantially constant.

The new device is constructed in such a manner that it is adapted to be used also for maintaining various predetermined pressures if adjusted accordingly.

The accompanying drawing illustrates one mode of application of the device according to the invention and the arrangement of its essential constituent parts, Figure 1 is a vertical section view of the lower part of the apparatus, and Figure 2 is a vertical section view of the upper part of the apparatus 50 above section AA of Figure 1. Fig. 3 is a

diagrammatical view illustrating the complete apparatus in a simplified manner.

The regulator proper, consists of a container 1 for liquid in which is mounted a cap 2, the lower edge of which is at an angle to the horizontal. Around a circular opening in the bottom of the container 1 is a tubular piece 3 reaching into the interior of the cap 2 and being provided with lateral openings 4. To the lower edge of the tubular piece 3 is connected a tube 5 leading to the furnace of the boiler. The upper opening of the container 1 may be provided with a rotatable slide valve 6 for roughly adjusting the entrance of air. The air enters from above into the container 1, flows down around the exterior of the cap 2 and beneath the lower edge into the interior of the cap, from there through the openings 4 into the tubular piece 3 and through the tube 5 to the furnace. In case of the liquid, preferably water, standing only so high in the container 1 that the edge of the cap 2 is completely free, the cross-section of the air passage is a maximum and the maximum quantity of air may flow to the furnace. The higher the liquid rises, the smaller becomes the cross-section of the air passage and in case of the cap edge immersing totally into the liquid, the air can no longer enter into the interior of the bell and the flow of air is interrupted.

The container 1 of the regulator communicates by means of a pipe 7 with a reserve vessel 8 in which normally the level of the liquid is at the same height as it is in the container, viz at such a height that the cap is out of contact with the water. If the pressure in the reserve vessel 8 increases, the liquid is partly driven out and the level lowers, whereas the liquid in the regulator container thereby rises, so that it is only necessary to make the pressure in the reserve vessel 8 depend on the pressure in the boiler for having the air supply to the furnace controlled by the steam pressure in the boiler.

With this object in view the air space of the reserve vessel 8 is connected by means of a pipe to a vessel 9 having a downwardly extending tube 10, which is open at its lower end and is slidably inserted in a tube 11, arrangement being made that the tube 10 fits tightly in the tube 11. This latter has a branch 12 leading to the water filled part of the steam boiler or to a container, the

liquid of which is under the pressure of the boiler. Therefore the water in the tube 11 is at a level corresponding to the pressure in the steam boiler. The tube 11 is of such height that under normal operating conditions, it is nearly completely filled with the water of the boiler, which also penetrates from below into the tube 10. The communication between the air space of the reserve vessel 8 with the air space of the vessel 9 is effected by means of the following device: By a pipe 13 extending upwards from the bottom of the reserve vessel 8, this pipe being open at both of its ends, and connected at its lower end with a pipe 14, a fitting 15 and a vertical pipe 16 which passes through the vessel 9 and has an upper open end, the upper part of this pipe 16 being surrounded by a tube of a somewhat larger diameter which is closed at its upper end and is mounted on the cover of the vessel 18. In this way, the air space of the vessel 9 communicates with the tube 16 by interstices left between this tube 16 and its surrounding tube 17, this air passage being indicated by arrows.

When the furnace is fired, the pressure in the boiler increases gradually, the water in pipe 10 rises without practically increasing the air pressure in the vessel 9 on account of this pipe being comparatively small and therefore only a small quantity of air is displaced by the rise of the water. Consequently, the liquid in the reserve vessel 8 is not exposed to a substantially increased pressure and the regulator is therefore not appreciably actuated. The air supply passages of this regulator remain entirely open so that the intensity of the furnace firing is maintained. The rise of the column of water in the tube 10 in consequence of the increase of the pressure in the boiler is independent of the cross-section of this tube, i. e.: To every degree of pressure corresponds a certain height of the column of water, no matter how large be the cross-section of the tube communicating with the boiler. However the increase of the volume of water in this tube produced by the rise of the column of water, when the pressure increases, depends upon the cross-section of the tube. If it is assumed that the boiler pressure begins to increase at a uniform rate when the level of the liquid in tube 10 is below the bottom of vessel 9, the height of the level of the liquid in tube 10 will increase in proportion to the increase in boiler pressure. If the friction of the pipe connections be neglected, this relation between the height of the level of the liquid and the boiler pressure remains constant, as the level of the liquid rises in tube 10 and in the vessel 9. The increase in the height of the level of the liquid is always proportional to the increase in boiler pressure, regardless of the

cross-section of the passage in which the liquid is rising. A definite increase or decrease in boiler pressure will produce a correspondingly definite increase or decrease in the height of the level of the liquid in the regulating device, the change in the height of the level of the liquid being proportional to the change in boiler pressure, regardless of whether the level of the liquid is below the bottom of vessel 9 or above this point. It is therefore true that a certain change in the level of the liquid when this level remains below the bottom of vessel 9 will produce a very small displacement of fluid from the top of vessel 9, while the same change in the level of the liquid, when this level is above the bottom of the vessel 9, will produce a considerable displacement of the fluid in the top of vessel 9. In other words, a given change in boiler pressure will produce a slight displacement of the fluid in the top of vessel 9, when the level of the liquid flowing in tube 10 is below the bottom of vessel 9; and a considerable displacement of the fluid in the top of vessel 9, when the level of the liquid is above the bottom of vessel 9. For a given rate of change in boiler pressure, the rate of flow of the liquid in tube 10 is much greater of course when the level of this liquid is above the bottom of vessel 9 than when the level of this liquid is below the bottom of vessel 9. This sudden and large increase of volume causes a sudden increase of the air pressure in the vessel 9 on account of the sudden decrease of volume of the air space in this vessel. This increased air pressure rapidly forces the liquid in the reserve-vessel 8 through the connections 17, 16, 15, 14, 13, thus causing a rapid rise of the liquid in the container 1 of the regulator and simultaneously a rapid closing of the air passage. When the boiler pressure decreases, the decrease of volume will be considerable and cause a rapid opening of the air passage as long as the water is within the vessel 9. When the water sinks below the vessel 9, no further noticeable change in the regulator will take place, because the decrease of volume becomes less on account of the small cross-section of tube 10. In this way a predetermined pressure in the boiler may be precisely maintained.

To be more specific, the operation of the device is as follows: Assume that the apparatus is adjusted to regulate for a given pressure. If the pressure in the boiler is below this value the level of the liquid in the tubes 10 and 11 will be somewhat below the bottom of the vessel 9, and the cross section of the air passage in the regulator proper will be a maximum. When the pressure has increased to the given value, the level of the liquid in tube 10 will be even with the bottom of the vessel 9, and the air

passage will still be wide open. As the pressure increases beyond the given value, the height of the liquid will increase correspondingly. This increase in height causes 5 a large volume of the liquid to enter the vessel 9, due to its large cross section. This sudden change forces the fluid from the upper part of the vessel 9 through the communicating connections 17, 16, 15, 14 and 10 13 into the container 8. This causes an increase in pressure in this container 8, thus forcing the liquid therein through the pipe 7 into the regulator; and as the liquid rises in the regulator, the air passage is rapidly 15 closed. This shutting off of the air supply lessens the rate of combustion, and the pressure in the boiler decreases accordingly until the given value is reached.

In order to adapt the device for maintaining different degrees of pressure in the boiler, the vessel 9 may be adjusted to different heights. For this purpose the vessel 9 is guided along the pipe 16 which passes through it and is surrounded by a 20 chamber 18 having at its upper end a tubular extension 19 closed at the top. The pipe 10 is slidably mounted in the tube 11, and passes through a packing 20 in the bottom of chamber 18. When the vessel 9 is 25 adjusted to a higher level, the pressure in the boiler must become correspondingly higher before the water will enter the vessel 9. When the vessel is provided with an indicator movable along a vertical scale, 30 fixed on the outward side of chamber 18 and indicating the boiler pressure to be maintained, it is possible to so adjust the height of the vessel 9 that the regulating device 35 will regulate for any desired boiler pressure.

40 In order to obviate the loss of the liquid by evaporation a film of oil 21 may be put on the surface of the liquid in the regulator vessel 1.

45 It is understood that I do not limit myself to the described details of construction which might be modified in various ways without departing from the spirit of the present invention.

50 What I do claim as my invention and desire to secure by Letters Patent is,

1. In a device of the character described having an air passage, the combination of a regulator proper for varying the cross-section of the air passage, and fluid pressure means for actuating the regulator proper, said means comprising a reserve vessel for holding a liquid, a pipe connection between the lower part of said reserve vessel and said regulator proper, a vessel of relatively large cross-section, a pipe connection between the upper part of said reserve vessel of large cross-section, a pipe connection 55 of relatively small cross-section between the lower part of said vessel of large cross-section and the upper part of said vessel of large cross-section, and the boiler, said pipe connection being normally filled with a liquid up to the bottom of said vessel of large cross-section.

2. In a device of the character described 70 having an air passage, the combination of a regulator proper for varying the cross-section of the air passage, and fluid pressure means for actuating the regulator proper, said means comprising a reserve vessel for 75 holding a liquid, a pipe connection between the lower part of said reserve vessel and said regulator proper, a vessel of relatively large cross-section, a pipe connection between the upper part of said reverse vessel 80 and the upper part of said vessel of large cross-section, a pipe connection of relatively small cross-section between the lower part of said vessel of large cross-section and the boiler, said pipe connection being normally 85 filled with a liquid up to the bottom of said vessel of large cross-section, and said vessel of large cross-section being adjustable to any desired height.

3. In a device of the character described 90 having an air passage, the combination of a regulator proper for varying the cross-section of the air passage, and fluid pressure means for actuating the regulator proper, said means comprising a reserve vessel for 95 holding a liquid, a pipe connection between the lower part of said reserve vessel and said regulator proper, a vessel of relatively large cross-section, a pipe connection between the upper part of said reverse vessel 100 and the upper part of said vessel of large cross-section, a pipe connection of relatively small cross-section between the lower part of said vessel of large cross-section and the boiler, said pipe connection being normally 105 filled with a liquid up to the bottom of said vessel of large cross-section, and said pipe connection between the lower part of said vessel of large cross-section and the boiler being adapted to permit adjustment of said vessel at any desired height.

4. In a device of the character described, a regulator proper for controlling the supply of air to the furnace, a pipe of relatively small cross-section communicating 110 with the boiler, a vessel of relatively large cross-section communicating with said pipe, and a reserve vessel for holding a liquid, communicating with said vessel of large cross-section and with said regulator proper, said vessels and pipe being arranged 115 so that changes in boiler pressure near a predetermined value will produce a rapid flow of the liquid between the reserve vessel and regulator proper, while corresponding 120 changes in boiler pressure considerably below the predetermined value will produce only slight flow of the liquid.

In testimony whereof I affix my signature.
ING. SIEGFRIED DEUTSCH.
